UNITED STATES PATENT OFFICE.

CHARLES CAMPBELL, OF LONDON, ENGLAND, ASSIGNOR, BY MESNE ASSIGNMENTS, TO THE TABULATING MACHINE COMPANY, OF NEW YORK, N. Y., A CORPORATION OF NEW JERSEY.

RECORD-CARD-OPERATED STATISTICAL MACHINE.

Application filed May 16, 1923, Serial No. 639,359, and in Great Britain July 21, 1922.

This invention relates to record-card-operated statistical machines, of which the well-known Hollerith tabulating machines are examples.

5 In the use of such machines, it may in certain circumstances be desired to accumulate, print or list quantities represented by perforations in the cards only from those cards of a series which have a particular hole 10 or combination of holes, and from no others; and the procedure hitherto has been to sort out these cards in a sorting-machine, which may be provided with one or more single-column selectors, consisting, for example, of 15 a switch-member moved in synchronism with the record-card and adapted to close the card-circuit momentarily during its movement, there being means whereby such closing may be made to occur when any pre- 20 determined one or more of a column of index-points is opposite the brush of the card-reading means.

Thereupon the sorted-out cards are passed through a quantity accumulating tabulating 25 machine or printing tabulating machine, and thereafter reaggregated with the remainder in their original order.

The object of the present invention is to 30 enable the selecting and quantity-tabulating (or printing) operation to be effected in one operation, and without the necessity of sorting out or segregating the cards to be selected and of subsequently re-aggregating them.

35 Preferably the operation is carried out while the record cards are in continuous motion through the machine thus obviating the necessity of stopping the feed of the cards to take a selector reading therefrom.

40 Accordingly the present invention consists of a machine comprising in combination two card-reading mechanisms (for example, two sets of card-contacts and circuits) one or more single-column selectors associated with one of the mechanisms whereby 45 said mechanism is rendered operative only when a certain pre-selected hole or combination of holes is present in a card; quantity-accumulating devices (for example quantity- 50 counters or printing devices) controlled by the second card-reading mechanism, and operative connections between the first and second card-reading mechanisms whereby the second mechanism is rendered operative

only when the selector-controlled first mechanism is operative.

The operative connection aforesaid may consists of a relay-switch or switches, operated by selector-controlled card-circuits of the first card-reading mechanism and controlling card-circuits of the second mechanism.

55 Preferably the selector-controlled card-circuit or circuits control as aforesaid an intermediate circuit which is itself operatively connected to the second set of card-circuits. This intermediate circuit may be provided with a mechanically-operated switch timed to operate after the perforations of each card have passed the first 60 brushes, whereby the intermediate circuit is maintained inoperative until the proper time.

A card sorting device may be placed in this intermediate circuit or in a circuit controlled thereby, so that the cards may if desired be sorted, in accordance with the selection, immediately after the tabulating or printing operation and without further setting of the machine or other manual operation.

65 The single-column selector which it is preferred to employ, and which forms a further feature of the invention, comprises a rotating contact geared to rotate synchronously with the passage of a card through the apparatus and adapted to bridge a gap in the brush circuit at one point of its movement, and means for adjusting the angular relation between the contact and the gap in the circuit (for example by adjusting the segment about 70 its axis of rotation) whereby any one of a column of index-points may be selected at will.

75 In order to enable a combination of index-points in different columns to be selected as aforesaid, a plurality of such selecting devices is employed each controlling one of a number of relay switches in series in a circuit which controls the counting and/or other mechanism. One of the selecting devices is placed in each of the brush circuits corresponding to the desired columns of index-points, and each device is adjusted to 80 select the particular index-point from the corresponding column. It will be readily seen that the counting and/or other mechanism will not operate unless all the relay switches are closed, and this will not occur

unless the predetermined combination of index-points is present on the card. Thus only those cards having this particular combination are counted, sorted out or otherwise dealt with.

A preferred form of tabulating machine according to this invention is illustrated in the accompanying drawings, in which

Figure 1 is a diagrammatic view showing 10 the parts of the machine and the various circuits displayed for the sake of clearness.

Figure 2 is a plan of part of a single-column selector, and

Figure 3 is a section on the line 3—3 in 15 Figure 2, looking in the direction of the arrows.

Referring to Figure 1, an upper set of card-contacts is represented by two contacts 4, and a lower set by three contacts 6. These 20 contacts are of well-known form and will not be further described, it being understood that there are as many contacts side-by-side in each set as there are columns of index-points on the record-card. The usual card-feed mechanism is employed whereby record-cards can be fed downwards one by one between the contacts 4 and then through the contacts 6. There is a gap, not less than the vertical dimension of a card, between the 25 two sets of card-contacts.

A driving motor 8 is supplied with current from the supply mains 10 and 12 by means of main leads 14 and 16, between which leads all the circuits to be described 30 extend.

Current is supplied to the brush-contacts 4 from the lead 14 through cam-contacts 18, line 19, contacts of a relay 20, and individual brush-leads 22. The cam-contacts 18 are 35 timed to open when the brushes 4 make contact in the gap between successive cards, being closed at all other times. A number of single-column selectors 24 are provided any one of which can be connected with any one 40 of the contact-blocks 4^a by means of plug-connections 26. Each selector is connected to the lead 16 through a holding-relay 28 and a relay winding 30, the contacts 32 of which are separately shown in series in a line 34 which constitutes an intermediate circuit.

The winding of the relay 20 is in a shunt 36, through a card-lever-contact 38 of ordinary form, to the line 19. Thus, as soon as a card passes this card lever, the relay 20 45 will be energized, thereby permitting all circuits through the contacts 4 and selectors 24 to be completed under the joint control of the card-perforations and the selectors.

Assuming that only the two selectors shown are being used, the contacts 32 corresponding to the unused selectors are short-circuited by means of hand-operated switches 40, as shown. If there are perforations in a card at the particular points 50 in the particular columns for which the two

selectors have been set, the corresponding relays 30 will be energized and the two corresponding contacts 32 will be closed.

At the same time the two holding-relays 28 will be energized, thereby closing hold-circuits 29 shunting the contacts 4, and maintaining the contacts 32 closed.

As soon as all index points in the columns dealt with have passed the brushes 4, and the changes have been effected by the index 75 perforations, the cam-contacts 42 close, thereby completing the auxiliary circuit through the two pairs of closed contacts 32.

As the cam-contacts 18 open immediately after this, a holding circuit is necessary for 80 the circuit 34, and this is provided by the relay 44, shunt 46 and cam-contacts 48, the function of the latter being to re-open the circuit and de-energize the relay 44, (at the end of the tabulating card-cycle to be de- 85 scribed later) ready for the next card.

It will be understood, of course, that if a card has not the pre-selected perforations, one or both of the contacts 32 will remain open, and the intermediate circuit 34 will 90 not be completed.

This intermediate circuit is employed to control tabulating or other operations of the lower set of card-contacts 6, whereby such operations only take place in connection with cards having the said preselected perforations, as will now be described.

The common bar 50 of the brushes 6 is connected to the lead 14 through contacts 52 of a relay the winding 54 of which is in the 100 intermediate circuit 34, and it will be evident at once that since the card-contacts 6 will not complete brush-circuits unless the contacts 52 are closed, and since, only when a "selected" card has passed the upper card-contacts 4, the relay 54 is energized during the time this card is passing the lower card contacts 6, the arrangement described attains the desired result.

The line from the contacts 52 to the lead 110 14 includes a pair of card-lever-contacts 56 and cam-contacts 58 timed to open when the card-contacts 6 close between two successive cards. Further, there is a shunt 60 containing the winding of a holding-relay 62 for a holding-circuit bridged across the card-lever contacts 56, as shown.

Quantity-counters, printing devices or the like are actuated in accordance with the card-perforations and in the usual manner 120 by means of magnets of which the windings are shown at 64.

The card-lever-contacts 56 are employed to stop the machine when the last card has passed. The line from the lead 14 to the motor includes starting-key contacts 66, a motor-relay winding 68 and stop-key contacts 70 and 72. It will be evident that once the starting-key has been depressed a shunt 74 will be closed by the contacts of 130

the relay 68, and the starting-key may therefore be released.

The motor now remains under the joint control of cam-contacts 76 and relay-contacts 78, the magnet-winding 80 of which is in the shunt 60 previously described.

Since the shunt 60 is interrupted by the cam-contacts 58 once per cycle, the contacts 78 will open once per cycle. Hence the cam-contacts 76 are timed to close when 58 are opened. After the last card passes the lower card-lever, the contacts will remain open, and the next time the contacts 58 close the winding 80 will receive no current. Consequently, the relay-contacts 78 will be open at the same time as the cam-contacts 76 and the contacts of the motor relay 68 will open, thus finally stopping the machine.

Counters are employed to count the total number of cards passing through the machine and the number of cards selected by the contacts 4 and the selectors 24, and, as a check upon these two, a counter for cards not selected.

The total-card counter may be a units counter the magnet-winding 82 of which is placed in the shunt 36. A units counter for selected cards may have its magnet-winding in the intermediate circuit 34.

If ordinary Hollerith or like quantity-counters are employed for card-counting, they are placed in circuits in parallel with the contacts 6 under the control of cam-contacts timed to close momentarily at the "1" position of the counters.

In this arrangement, the winding 84 of the "total-card" counter is in a line 86 shunted across the contacts 52 and the lower card-contacts 6, the cam-contacts, timed as aforesaid, being shown at 88. The magnet-winding 90 of the counter for "selected" cards, and its cam-contacts 92, are in a line 94 shunted across the contacts 6 but in series with the contacts 52. The counter for "non-selected" cards, and its cam-contacts, are indicated at 96 and 98 respectively in a line 100 similar to the line 86, and this counter is short-circuited and therefore not operated, every time the circuit 34 is completed, by a line 102 having relay-contacts 104 the magnet-winding 106 of which is placed in the said circuit 34.

The cams operating the cam-contacts 18, 42, 48, 58, 76, 88, 92 and 98 are preferably all mounted on a single shaft 108, parts of which are indicated diagrammatically in Figure 1, which is driven by gearing indicated at 110 from the motor 8. The card-feed rolls 112 are similarly driven by gearing indicated at 114, the gear-ratios being such that the shaft 108 rotates once per card-cycle, as is usual in machines of the Hollerith type. It will be understood that no attempt has been made to show the cams in their correct angular positions, but the ex-

planation of the timing of these cams given above will enable those skilled in the art to understand the construction.

If it is desired to sort out the "selected" cards after they have passed through the machine, a card-sorting device, indicated diagrammatically at 116, is placed to receive the cards from the lower card-contacts 6. This sorting device may be of any well-known kind, and is therefore not described in detail. Its controlling-magnet-winding may be placed in the circuit 34 as shown, or in the line 94, and in either case, as will be evident to those skilled in the art, it will operate to segregate the "selected" cards from the others.

Referring now to Figures 2 and 3, the preferred form of single-column selector comprises a drum 3 of insulating material provided with two grooves 5 and having let into it a metal bar 7 flush with its periphery and grooved to correspond.

The drum 3 is mounted to rotate on a shaft 9 which is rotated in the direction of the arrow, in synchronism with the card-feed-rolls 112 (Figure 1) by the gearing 114, and which drives the drum through the one-way clutch 13 held yieldingly in engagement by the spring-pressed lever 15.

Two fixed brushes 17 bear upon the bottoms of the grooves 5, and these brushes are placed in the leads from the blocks 4^a, as clearly shown in Figure 1.

The equally-spaced ratchet-teeth of the clutch 13 are so disposed that however the clutch is engaged, the metal bar 7 will be under the brushes 17 when an index-point in a card is at the card-contacts 4.

The drum 3 is further provided on its periphery with equally-spaced characters corresponding to the numbers, letters or the like by which the various index-points in a column thereof on a card are known. These characters are visible one at a time through a window 21 in a casing 23.

In order that the drum 3 may be angularly adjusted to select any desired index-point in the column, it is provided with a gear-wheel 25 which can be engaged by a pinion 27 fast to a knurled wheel 31.

The pinion and knurled wheel are mounted to rotate in the upper end of a pivoted lever 33 which when pushed towards the drum causes the pinion to engage the gear-wheel 25. Two detents 35 are provided one at each end of the shaft 9 which are moved into engagement with notches 37 in discs 39 fast to the shaft 9 whenever one of the levers 33 is pushed inwards, by means of a bail 41 extending between the detents 35 and engaged by each of the levers 33. Thus the shaft 9 is locked temporarily, and if the knurled wheel 31 is then turned in the direction of the arrow in Figure 3, the drum 3 can be rotated (the clutch 13 of course slip-

ping) until the required character on the drum is beneath the window 21. The lever 33 and the detent 35 are spring-pressed away from the shaft 9. In order to prevent undesired movement, a friction device 48 is provided which grips the gear-wheel 25. The angular relation between the notch 37, the teeth of the clutch 13, the bar 7 and the characters on the drum is such that when the drum has been thus rotated to bring a certain character beneath the window, the bar 7 will make contact between the brushes 17 during the running of the machine when the corresponding index-point is at the contacts 4, Figure 1.

Although only one drum 3 is shown, any number may be mounted on the shaft 9 side-by-side, each having a driving clutch and adjusting means as described and illustrated.

When it is desired to select more than one index-point in the same column of the cards, two or more selectors, each set for one such index-point, may be employed exactly in the same way as hereinbefore described when two or more index-points in separate columns are to be selected.

I claim:—

1. A record-card-operated statistical machine comprising in combination two card-reading mechanisms, one or more single-column selectors associated with one of the mechanisms in such manner that said mechanism is rendered operative only when a certain pre-selected hole or combination of holes is present in a card, quantity-accumulating devices controlled by the second card-reading mechanism and operative connections between the first and second card-reading mechanisms whereby the second mechanism is rendered operative only when the selector-controlled first mechanism is operative.

2. A machine as set forth in claim 1, wherein the operative connections comprise a relay-switch or switches arranged to be operated by the selector-controlled first card-reading mechanism and to control the second card-reading mechanism.

3. Controlling-means for record-card-operated statistical machines comprising in combination a card-reading mechanism, a plurality of single-column selectors associated therewith, an intermediate circuit, a plurality of relay-switches in series in said circuit, magnets for said relay-switches each in circuit with one of the selectors, and a device having itself no independent card reading mechanism adapted to deal with record-cards arranged to be controlled by said intermediate circuit.

4. A machine as set forth in claim 3, wherein the intermediate circuit is provided with holding-means and with a time-controlled switch operated in each card-cycle to

render the circuit effective for control of the device only after each card has passed the first selector-controlled card-reading mechanism.

5. In a machine as set forth in claim 4, holding-means in each selector-circuit and a time-controlled switch operated to de-energize and open the relay-switches after each card has passed the selector-controlled card-reading mechanism.

6. A record card-controlled statistical machine provided with a counter arranged to count all cards passing through the machine, a counter arranged in a selector-controlled circuit to count all selected cards, and a check-counter having a shunt across it which is provided with a relay-switch operated by a selector-controlled circuit to close said shunt and thereby short-circuit said check-counter each time a selected card passes, for the purpose described.

7. A record-card-operated statistical machine comprising in combination two card reading mechanisms, single column selectors associated with one of the mechanisms in such a manner that said mechanism is rendered operative only when a certain pre-selected hole or combination of holes is present in a card, quantity accumulating devices controlled by the second card reading mechanism, and operative connections between the first and second card reading mechanisms comprising a relay switch or switches arranged to be operated by the selector-controlled first card reading mechanism, and an intermediate circuit controlled by said relays which is itself operatively connected to the second card reading mechanism.

8. A machine as set forth in claim 7 where in the intermediate circuit is provided with holding means, and with a time-controlled switch operated in each card cycle to render the circuit effective for control of the device only after each card has passed the first selector-controlled card reading mechanism.

9. In a machine as set forth in claim 7, holding means in each selector circuit and a time-controlled switch operated to deenergize and open relay switches after each card has passed the selector-controlled card reading mechanism.

10. A perforated record-controlled machine including a plurality of record perforations sensing devices with provisions for sensing record cards while the latter are in motion through the machine, a selector means controlled by one of said record sensing devices, and a record-controlled means controlled for effective operation conjointly by the selector means and by the other record perforation sensing means.

11. A perforated record-controlled machine including a plurality of card sensing devices past which record cards successively

pass and which successively and independently read the perforations upon the cards, selector means controlled by one card sensing device, record-controlled means controlled by the other record sensing means, and means for controlling the effective operation of the last mentioned record-controlled means in accordance with the reading previously derived from the card by the selector means.

12. In a record-controlled machine, in combination with a settable selector device having provisions for comparing a card reading with a previous set-up of said selector, a card-controlled mechanism with provisions for control by a card after the same has imparted its reading to the selector device and means for controlling the last mentioned means by and in accordance with the previous comparing operation of the selector device upon said same card.

13. A record card operated machine in-

cluding a plurality of card reading devices one acting after the other upon the same card, record designating devices controlled by the second of said card reading devices and means for suppressing or permitting the action of said devices in accordance with the reading previously derived from the same card by the first card reading devices.

30

14. In a tabulating apparatus in combination, tabulating devices controlled by index points of record cards while the latter are in motion, and selector devices also operating upon the same cards and having provisions for selectively controlling the operation of the tabulating devices at the time the latter are being controlled by the same card which had previously passed and controlled the selector devices.

35

40

In testimony whereof I affix my signature.

CHARLES CAMPBELL.
